US0D1105913S

(12) **United States Design Patent** (10) **Patent No.:** **US D1,105,913 S**
(45) **Date of Patent:** **** Dec. 16, 2025**

(54) **BOTTLE CAP**

(71) Applicant: **Abbott Laboratories**, Abbott Park, IL (US)

(72) Inventor: **Roger W. Accurso**, Fremont, CA (US)

(73) Assignee: **Abbott Laboratories**, Abbott Park, IL (US)

(**) Term: **15 Years**

(21) Appl. No.: **29/939,790**

(22) Filed: **Apr. 29, 2024**

Related U.S. Application Data

(63) Continuation of application No. 18/436,718, filed on Feb. 8, 2024, which is a continuation of application No. 17/650,607, filed on Feb. 10, 2022, now Pat. No. 11,899,031, which is a continuation of application No. 16/551,163, filed on Aug. 26, 2019, now Pat. No. 11,293,936, which is a continuation of application No. 15/816,763, filed on Nov. 17, 2017, now Pat. No. 10,416,181, which is a continuation of application No. 15/141,187, filed on Apr. 28, 2016, now Pat. No. 9,823,263.
